[57] CLAIM

The ornamental design for transparent tire cover, as shown and described.

DESCRIPTION

FIG. 1 is a front perspective view of the transparent tire cover in its environment;

FIG. 2 is a top plan view of the tire cover;

FIG. 3 is a bottom plan view of the tire cover;

FIG. 4 is a back elevational view of the tire cover;

FIG. 5 is a front elevational view of the tire cover;

FIG. 6 is a side elevational view of the tire cover where the opposite side is a mirror image thereof.

The evenly spaced dashed lines in FIGS. 1–6 represent stitching, which forms part of the claimed design. The broken line showing of a vehicle in FIG. 1 is for illustrative purposes only and forms no part of the claimed design.
